US00D549744S

(12) **United States Design Patent** (10) **Patent No.:** **US D549,744 S**
(45) **Date of Patent:** **** Aug. 28, 2007**

(54) **PORTABLE, REFRIGERANT RECOVERY UNIT**

(75) Inventors: **Gregory S. Sundheim**, 5170 Juniper St., Bowmar, CO (US) 80123; **Robert M Morris**, Lakewood, CO (US)

(73) Assignee: **Gregory S. Sundheim**, Bowmar, CO (US)

(**) Term: **14 Years**

(21) Appl. No.: **29/271,010**

(22) Filed: **Jan. 8, 2007**

CLAIM

The ornamental design for a portable, refrigerant recovery unit, as shown and described.

DESCRIPTION

FIG. 1 is a perspective view of a portable, refrigerant recovery unit showing our new design.

FIG. 2 is a right side thereof, the left side view being a mirror image thereof.

FIG. 3 is a front view thereof.

FIG. 4 is a top plan view thereof.

FIG. 5 is a bottom plan view; and,

FIG. 6 is a rear view thereof.

The broken lines in the drawings are for illustrative purposes only and form no part of the claimed design.
